By Victor J. Evans

Attorney

UNITED STATES PATENT OFFICE.

GEORGE W. DAGGETT, OF NORTH GIRARD, PENNSYLVANIA.

PISTON.

1,216,955.

Specification of Letters Patent. Patented Feb. 20, 1917.

Application filed July 29, 1915. Serial No. 42,591.

To all whom it may concern:

Be it known that I, GEORGE W. DAGGETT, a citizen of the United States, residing at North Girard, in the county of Erie and 5 State of Pennsylvania, have invented new and useful Improvements in Pistons, of which the following is a specification.

This invention relates to pistons, the object in view being to produce a piston 10 which embodies lightness, strength and reliability and which may be produced at a comparatively small cost without any flaws and which will, therefore, wear better and longer than the ordinary piston as now constructed and which will furthermore have the same coefficient of expansion as the cylinder in which it is used thereby making the piston desirable for use in the engines of racing cars.

20 With the above and other objects in view, the invention consists in the novel construction, combination and arrangement of parts, as herein described, illustrated and claimed.

In the accompanying drawings:—

25 Figure 1 is a diametrical section through a piston constructed in accordance with the present invention.

Fig. 2 is a diametrical section through the apron of the piston illustrating the first 30 step in the method of manufacturing the piston.

Fig. 3 is a similar view showing the second step of forming the holes for the piston pin.

35 Fig. 4 is a similar view showing the third step of pressing the metal inward to provide for the bushings.

Fig. 5 is a similar view showing the bushings in place.

40 Fig. 6 is a diametrical section through the piston head which is drop forged.

Fig. 7 shows the second step in the formation of the piston head.

Fig. 8 shows the final step in the formation of the apron of the piston.

45 Fig. 9 is a modification of the form of piston head.

The piston is shown in its complete assembled form in Fig. 1 wherein 1 designates the apron or skirt of the piston which 50 has a general hollow or tubular cylindrical form, 2 the piston head which is rabbeted at 3 to receive the adjacent edge of the skirt or apron 1, 4 the bushings which are inserted through diametrically opposite holes in the apron 1, and 5 the piston pin to

which the connecting rod is attached in the general way.

The skirt or apron 1 of the piston is formed of stock tubing preferably of steel, 60 the same being cut to a suitable length to form an apron or skirt of the desired length as shown in Fig. 2. The next step consists in forming the holes 6 at diametrically opposite points in the apron to receive the bushings and piston pin. The next step 65 illustrated in Fig. 4 consists in pressing inwardly the opposite portions of the apron adjacent to the holes 6 to form inwardly extending offsets 7 which reinforce the walls 70 of the piston immediately adjacent to and around the bushings 4 above referred to, also leaving recesses or countersunk portions 8 in which the heads of the bushings are received as shown in Fig. 5 wherein the 75 next step in the method of production is shown to consist of inserting the bushings 4 so that the heads thereof lie flush with or slightly within the outer surface of the apron. Finally, the inner edge of the apron is flanged inwardly as shown at 9 to reinforce such edge of the piston.

80 The piston head 2 is made of a drop forging which produces the annular flange 10. The next step is shown in Fig. 7 which 85 consists in forming a rabbet 11 in the flange 10 to receive the corresponding edge of the apron of the piston. When the parts have been formed in the manner described, the bushings 4 are welded in the inwardly 90 pressed offsets 7 of the apron and the latter is then associated with the annular rabbet 11 in the head 2 and said parts welded together.

95 By means of the method hereinabove described, the piston is formed cheaply out of stock material and may be made lighter than the ordinary cast iron piston. Furthermore, the wall of the skirt or apron is of uniform thickness and there can be no flaws therein which result from defective castings. In this way the product is not only lighter in weight but is materially stronger in its construction and more durable in operation and has the same coefficient of expansion as the cylinder itself, thereby particularly adapting the completed piston for use in all engines particularly of the racing type.

100 In the modification shown in Fig. 9, a slight alteration is made over the formation described in the preceding figures, and,

as illustrated, a strengthening web 15 depends integrally from the head 2 and partially encircles the piston pin 5. Also formed in said head is a recess 16 designed to receive suitable piston rings 17 adapted to perform their usual functions.

Having thus described my invention, I claim:—

1. An engine piston comprising a drop forged head having an annular flange formed with an annular rabbet in the outer face thereof, a tubular apron having one edge welded in said rabbet, and also having diametrically opposite points thereof compressed inwardly to form apertured offsets, and headed bushings inserted through said offsets and welded therein with the heads thereof lying flush with the outer surface of the apron.
- 10
- 15

2. An engine piston comprising a drop forged head having an annular flange formed with an annular rabbet in the outer face thereof, a tubular apron having one edge welded in said rabbet and having its opposite edge flanged inwardly, and also having diametrically opposite points thereof compressed inwardly to form apertured offsets, and headed bushings inserted through said offsets and welded therein with the heads thereof lying flush with the outer surface of the apron.

In testimony whereof I affix my signature in presence of two witnesses.

GEORGE W. DAGGETT.
